MEANS FOR CHARGING TUBULAR CONTAINERS WITH MATERIALS

Edward Webster, Parkstone, England

Application January 10, 1950, Serial No. 137,688
In Great Britain January 11, 1949

11. Claims. (Cl. 226—27)

1. This invention relates to a method and means for charging tubular containers with salves and like liquid or plastic materials; more especially such materials as are usually required to have a moulded form so that they can be partially projected from the container for use. For example, tubular holders or containers for lip salves and other toilet salves are commonly provided with a cup movably arranged in the container and in this cup the base of a moulded stick of the material is inserted. The moulded stick is normally housed within the container and is enclosed by a cover until required for use whereupon the cover is removed and the cup is manipulated to project the end of the stick from the container.

An object of the invention is to provide an improved manner of charging such containers with the salves or like liquid or plastic or powdered materials according to which the material is placed in a chamber below which a number of tubular moulds are placed and, after receiving the material, are projected through the chamber and into co-axial relationship with the containers and caused to enter the containers whereupon air pressure is applied to the bases of the moulds to force the moulded material therefrom into the containers.

A further object of the invention is the provision of apparatus for carrying out the improved method of charging such containers with the aforesaid materials. This apparatus comprises a cylinder with a piston moving therein, the cylinder being closed above the piston by closure means provided with a series of apertures through which moulds attached to the face of the piston can be made to project. A chamber for the reception of the material to be charged is arranged on the closure plate of the cylinder in a position above the moulds and the moulds are projected through the chamber as the piston is moved within the cylinder on a charging stroke. The piston is provided with air passages through its face leading to the moulds secured therein and the cylinder below the piston is provided with a plurality of inlets for compressed air which is supplied below the piston after the latter has been moved forward on its charging stroke, the compressed air then entering the bases of the moulds in order to force the moulded material from the moulds into the containers. The apparatus further includes a removable means above the cylinder and piston in which the containers to be charged can be mounted and accurately located in relation to the moulds carried by the piston.

A preferred embodiment of construction of

2. apparatus according to the invention is illustrated in the appended drawings in which:

Figure 1 is an elevation with half in vertical section of a cylinder and piston and a carrier for the containers.

Figure 2 is a plan thereof with a portion of the carrier plate for the containers broken away in order to expose to view a number of moulds which are carried by the piston.

10. In this apparatus 10 is a cylinder closed at the bottom except for a central opening 11 in which a bearing sleeve 12 is provided to receive a piston rod 13 secured to a piston 14 whose periphery is a moving fit in the cylinder 10. The upper end of the cylinder is closed by a closure plate 15 secured by the bolts 16 and provided with a number of holes 17.

20. The piston 14 is provided with a number of openings 18 which are co-axial with the holes 17 in the closure plate 15 of the cylinder and the upper face of the piston is recessed as at 19 around each opening 18 to receive the flanged bases 20 of tubular moulds 21. The tubular moulds 21 and the openings 18 correspond in number with the holes 17 in the closure plate 15. The flanged bases of the moulds 21 are secured to the piston by a clamping plate 22 secured by a number of attachment screws 23. The moulds 21 thus project from the leading face of the piston and are a sliding fit in the holes 17 and, when the piston is advanced within the cylinder 10 to the position shown in Figure 1, the moulds pass through the said holes 11 and project well beyond the closure plate. On the withdrawal of the piston from the closure plate 15 towards the lower end of the cylinder the moulds are withdrawn until in the lowermost position of the piston the upper ends of the moulds are flush with the upper surface of the closure plate 15.

30. 35. 40. Each mould 21 is open at the end remote from the piston and has an internal "form" 24 of a shape which it is desired to give to the moulded materials when charged into the containers. Each mould further has a fine air inlet 25 in its base leading to the internal form 24 and below that a larger opening 26 which is in direct communication with the openings 18 through the piston.

45. 50. On the upper face of the closure plate 15 of the cylinder an open chamber 27 of annular form is provided by securing an outer ring plate 28 to the closure plate, for example by the bolts 16 already referred to, and by a central circular plate 29 secured to the closure plate by screw bolts 30. This annular chamber 27 extends over the

area through which the moulds are projected as the piston is moved outwardly and into this chamber the liquid or plastic material, for example lip salve for producing lip sticks, is placed when the piston and the moulds are retracted below the chamber and with the open ends of the moulds flush with the top of the closure plate 15 which forms the bottom of the chamber 27.

Above the assembly of cylinder, piston, moulds and the material-receiving chamber, a carrier plate 31 is suitably spaced by distance blocks 32, say three in number, secured to the plate by screws or the like and is located by two or more dowels 33 projecting from the ring plate 28. In this carrier plate 31 are a number of apertures 34 corresponding with the moulds 21 and co-axial therewith and an annular shallow recess 35 is formed in the plate 31 above the apertures 34. This plate 31 serves to carry a number of containers as for example a lip salve container 36 into which the salve or like material is to be charged. The containers as shown are provided with portions 37 and 38 of different diameters so that when the parts 38 are fitting the apertures 34 the larger diameter parts 37 are accommodated in the annular recess 35 and the shoulder between the parts 37 and 38 rests on the base of the recess and supports the containers in the carrier plate. Above the carrier plate 31 a removable cover plate 39 is provided which can be clamped by a milled nut 40 on a screw 41 secured in and projecting above the circular plate 29.

It is preferred to provide a slotted washer plate 42 below the milled clamping nut 40 to apply the pressure of the nut to the cover 39 so that by releasing the nut and sliding out the slotted washer plate, the cover can readily be removed for placing or replacing the containers in the carrier plate 31.

A number of air inlets 43 are formed at equidistant points through the wall of the cylinder 10 and flexible pipes 44 are connected to these inlets 43 by suitably screwed nozzles 45, the flexible pipes communicating with any suitable source (not shown) of compressed air. The flexible supply pipes should all be of approximately the same length in addition to being evenly distributed around the cylinder with the object of effecting a simultaneous charge into all parts of the cylinder below the openings 18 leading to the openings 26 in the bases of the moulds and to the fine air inlets 25 communicating with the internal form 24 of the moulds. The compressed air supply pipes 44 between the source of air supply and the inlets 43 of the cylinder 10 may be coupled to a union box of well known construction (not shown) in which a two way valve may be provided so that the box can be placed either in communication with the compressed air supply source or with the atmosphere as desired. By this means the cylinder 10 can be vented to atmosphere, but if desired a release tap 46 can be provided communicating with the interior of the cylinder.

In operation the cover and carrier plate are lifted from the apparatus and the piston 14 is retracted to its lowest position in the cylinder 10 so that the upper ends of the moulds 21 are flush with the upper surface of the closure plate 15 of the cylinder and thus are at the bottom of the chamber 27. The chamber is then filled with the material and the material is run or rubbed into the open moulds to fill the internal forms thereof. The carrier plate 31 in the meantime has been filled with containers 36 in all its openings 34 and this is replaced on the apparatus and the

cover plate 39 is clamped into position. The piston is then advanced to project the moulds through the chamber 27 and into the co-axial containers 36.

5 In the example illustrated the containers 36 are for the reception of lip salve and as such are usually provided with internal cups 47 movable in the container in known manner. The moulds enter the containers until their upper lips meet the downwardly directed lips of the cups 47 therein. Compressed air is then admitted through the flexible pipes 44 to the cylinder below the piston 14 and the air passes through the fine apertures 25 into the moulds and blows the moulded materials from the moulds into the cups.

10 The piston is then retracted to withdraw the moulds from the containers and into the cylinder below the bottom of the charging chamber. The cover 39 and carrier plate 31 are lifted off the apparatus and the charged containers removed from the carrier plate. The chamber 27 is recharged with filling material and another carrier plate loaded with containers is placed in position for the operation to be repeated. For the removal of the containers from the carrier plate a stripping plate such as indicated at 48 can be provided so as to lift all the containers simultaneously from the carrier plate.

15 It will be understood that any suitable means for moving the piston 14 can be provided. As compressed air must be available for the apparatus it is convenient to employ a double acting air cylinder (not shown) of known form for raising and retracting the piston. The piston rod 13 is shown of substantial diameter with a long bearing sleeve 12 to ensure its smooth and true axial movement relatively to the cylinder. Below the bearing sleeve, the rod may be provided with a connecting rod 49 of smaller diameter which is operated by the piston of the double acting air cylinder.

20 The illustrated arrangement allows moulds of different external and internal diameter to be used with the standard piston by exchanging the clamping plate 22 for one having appropriately sized apertures for the moulds to be placed in position. All the moulds would have a standard base fitting the recess 19 in the face of the piston 14.

25 It will be understood that the fine passages of the moulds may vary with the capacity of the moulds. As one example of a suitable bore 25 for a mould having a parallel cylindrical cavity of a diameter of 0.375", except for a tapering or inwardly curved lower end as marked 50 in Figure 1, a dimension of 0.013" has been used. An air pressure of 80 to 100 lbs. to the square inch has been used, but lower pressures will operate satisfactorily.

30 The surrounding lip of the mouth of a mould may be given a slight lead to receive the lip of a cup 47 or the rim of each cup may be pressed or formed with a slight lip to receive the lip of the mould so as to facilitate the charging operation.

35 The improved method and means enable the containers to be charged with much less labour at greater speed and result in more uniform and accurate charging of the cups and moulding of the materials.

40 I claim:

45 1. An improved method of charging tubular containers with salves and like liquid or plastic materials or powdered materials in a condition capable of being moulded, according to which

tubular moulds capable of entering the containers from below whilst the containers are held in inverted position in axial alignment with the moulds are filled with the material and moved upwardly into a stationary position where they are received in the lower parts only of the inverted containers, whereupon the interiors of the moulds are subjected to air pressure to displace the moulded material from the moulds and charge the containers therewith, in which charged condition of the containers the material is retained against displacement in the upper ends of the containers and the air pressure on the material is relieved, whereupon retraction of the moulds from the filled containers is effected.

2. An improved method of charging tubular containers with salves and like liquid or plastic materials more especially materials required to have a moulded form so that they can be partially projected from the containers for use, according to which the material is placed in a chamber above a cylinder containing a piston, carrying a plurality of tubular moulds, and below a carrier in which the containers are secured in inverted position and the piston is moved upwardly to bring the moulds into co-axial relation with the containers and cause them to enter the lower portions of the containers whereupon air pressure is applied to the cylinder and permitted to enter the moulds through the piston in order longitudinally to displace the moulded material therefrom and charge it into the containers, in which charged condition of the containers the moulded material is retained against displacement in the upper ends of the containers and the air pressure on the material is relieved, whereupon retraction of the moulds from the filled containers is effected to permit removal thereof from the carrier.

3. Improved apparatus for charging containers with salves and like materials comprising a cylinder with a piston moving therein, closure means for the cylinder above the piston and apertures through said closure means, co-axial apertures in the piston, tubular moulds arranged in the face of the piston each of said moulds having a base flange and the piston having a recess in its face co-axial with each of its apertures in which recess the base of a mould is inserted and secured by a perforated clamping plate secured to the piston, apertures in the base of the moulds communicating with the apertures in the piston, an internal form in the mould cylindrical in its upper portion and tapering to its lower end, a relatively fine bore between the aperture in the base of the mould and the internal form; a chamber for the reception of the materials above the closure means of the cylinder and over the said moulds in the piston when the piston is in its lowermost position, means for carrying the containers to be charged so that they are in line with the various moulds supported by the piston, means for moving the piston and the moulds towards the said carrier for the containers, means for retracting the piston and moulds, and means for admitting compressed air to the cylinder below the piston so that the air has access to the interior of the moulds, such compressed air being admitted to the moulds after the latter have been filled with material and moved by the piston so as to enter the containers, whereby the moulded materials are charged into the containers.

4. Improved apparatus for charging containers such as lip salve containers with salves and

like material comprising a cylinder closed at the base, a piston within the cylinder and movable by means of a rod moving in a bearing provided in the closed base of the cylinder, a plurality of openings through the piston and a corresponding number of tubular moulds supported by the piston and communicating with the openings therein, a circular closure plate for the top of the cylinder and apertures through the plate corresponding in number with the openings through the piston and of a size to receive the moulds supported by the piston, an annular chamber above the closure plate for receiving the material to be charged said chamber being formed by an outer ring secured to the closure plate and a central circular plate co-axial with the ring, the annular chamber being positioned so that the material in it can enter the moulds in the apertures of the closure plate when the piston supporting the moulds is in its lowermost position, a carrier for the containers spaced above the aforesaid chamber and having means for supporting and locating the containers with their open ends in line with the moulds, and

means for supplying compressed air to the cylinder below the piston when the latter is raised to cause the moulds to enter the containers whereby said air is applied to the moulds to displace the material moulded therein so as to charge the containers.

5. Improved apparatus for charging tubular containers with salves and like liquid, plastic or powdered materials, such as lip salve containers each having a material-receiving cup normally disposed at one end of the container, comprising a receptacle for the materials to be charged, means for removably supporting the containers in inverted position with the cups uppermost, a plurality of tubular moulds arranged co-axially with the containers and of a size to enter the containers, each mould having a capacity to accommodate sufficient material to charge a container, means for moving the moulds into a position where the material from the receptacle can enter the moulds and for advancing the moulds through the receptacle and towards and into the respective containers to abut against the cups, means for enabling compressed air to be applied to the material in the moulds when the moulds are within the containers so as to discharge material from the moulds into the containers where it is retained in the cups disposed above the moulds, and means for retracting said moulds from within the containers to a position where the moulds are disposed below the receptacle.

6. Improved apparatus for charging containers as specified in claim 5 wherein each mould has an opening in its base, a cylindrical interior leading from the upper end of the mould and tapering towards the base of the mould, and a fine internal bore communicating at one end with the opening in the base and at the other end with the tapered end of the interior of the mould.

7. Improved apparatus for charging containers with salves and like materials comprising a piston working in a cylinder having an apertured closure plate, a material receptacle surmounting the closure plate and communicating with the apertures therein, apertures in the piston co-axial with the apertures in the closure plate, tubular moulds secured in the upper face of the piston and communicating with the apertures therein, said moulds being adapted to enter the

75

apertures in the closure plate, means for removably supporting the containers in inverted position where they are above the piston and in axial alignment with the moulds, means for retracting the piston to a lowermost position in which the moulds are below the receptacle and can be filled with material from the receptacle, means for raising the piston to an uppermost position during which rising movement of the piston the moulds move through the receptacle and enter the lower ends of the containers, and means for admitting air under pressure to the cylinder below the piston so that the compressed air has access to the interior of the moulds by way of the apertures in the closure plate and discharges material from the moulds into the containers in the upper ends of which it is retained.

8. Improved apparatus for charging containers as specified in claim 7 wherein the cylinder is provided with a number of inlet openings in the cylinder wall to which compressed air is led by a corresponding number of flexible pipes communicating with a compressed air supply, said inlet openings being so disposed in the cylinder wall that they are covered by the wall of the piston when the piston is retracted, and means for venting said cylinder to atmosphere.

9. Improved apparatus for charging containers as specified in claim 7 wherein the means removably supporting the containers in inverted position comprises a removable plate recessed in its upper surface, apertures in the recessed plate extending from the under surface thereof to the base of the recess, said apertures in the recessed plate corresponding in number and position with the apertures in said closure plate, and a removable cover plate surmounting the recessed plate and adapted to retain the containers when placed in the apertures of the recessed plate.

10. Improved apparatus for charging containers, such as lip salve containers, with salves and like materials comprising, in combination, a cylinder and piston, a carrier mounted in fixed position above the cylinder and piston for releasably supporting a plurality of containers in inverted position, an apertured closure plate at the upper end of the cylinder, a material receptacle interposed between said closure plate and carrier, said receptacle being mounted on the cylinder, apertures in the piston communicating with the apertures in the closure plate, hollow moulds supported on the piston and communicating with the apertures in the piston, said moulds being received and guided in the aper-

tures in the closure plate, means for moving said piston towards or away from said closure plate, during which movement of the piston towards the closure plate the moulds enter the lower ends of the containers, a base plate at the lower end of said cylinder said base plate serving to close that end of the cylinder and act as a stop against which the piston abuts when retracted, in which retracted position of the piston the upper ends of the moulds are disposed below the receptacle and communicate therewith so that material contained in the receptacle can be loaded into the moulds, and means for supplying compressed air to the cylinder below the piston when the latter is raised to cause air under pressure to be applied to the interior of the moulds to discharge material moulded therein into the inverted containers where it is retained in the upper ends of said containers.

20 11. In an apparatus of the type described for charging tubular containers with salves and like liquid, plastic or powdered materials, the combination of a receptacle for the material to be charged, said receptacle being open on top and provided with a plurality of apertures in its bottom, a first carrier adapted to be secured to said receptacle above the latter and in spaced relationship thereto, said carrier including means for supporting said containers in an inverted position and in registry with said apertures of said receptacle bottom, a second carrier reciprocable underneath said receptacle in a vertical direction, a plurality of moulds open on top and supported by said second carrier and shiftably fitting said apertures and into said containers, means to reciprocate said second carrier between a first end position in which the open ends of said moulds are flush with the inner face of said receptacle bottom, and a second position in which said moulds extend at least a substantial length into said containers, and means to apply compressed air to material in said moulds through holes in the bottom of said moulds and registering ducts in said second carrier.
